UNITED STATES PATENT OFFICE.

WILLIAM H. FAUBER, OF CHICAGO, ILLINOIS.

DESIGN FOR A SPROCKET-WHEEL FOR BICYCLES.

SPECIFICATION forming part of Design No. 31,194, dated July 11, 1899.

Application filed June 17, 1899. Serial No. 720,994. Term of patent 7 years.

To all whom it may concern:

Be it known that I, WILLIAM H. FAUBER, residing in the city of Chicago, county of Cook, and State of Illinois, have invented and produced a new and original Design for a Sprocket-Wheel for Velocipedes, of which the following is a specification, reference being had to the accompanying drawing, forming a part hereof.

10 The drawing illustrates in side elevation a sprocket-wheel made in accordance with my design.

The essential or characteristic features of a sprocket-wheel made in accordance with my design consist of an outer circular rim having on its periphery a plurality of openly-spaced radial projections or sprocket-teeth, three similar and equal partial rings or annulus-segments connected with the rim and 20 extending radially inward therefrom, with their centers disposed symmetrically about the center of the wheel, and three smaller and similar annulus-segments, one located intermediate with respect to each two adjacent 25 larger segments and between the same and the rim. Each of said segments, both the larger and smaller ones, includes the greater part of a circle, and the ends of said segments are separated by spaces at their radially-outer 30 portions adjacent to the rim, their said ends being joined to the inner margin of the rim at circumferentially-separated points. The larger segments are joined at their radially- inner parts to a centrally-arranged center

piece or hub, which is provided centrally 35 thereof with a circular aperture. Each smaller segment is joined at its external margin, on each side thereof and radially inside of its center, to the external curved margin of the adjacent larger segment, and between each 40 smaller segment and adjacent larger segment on the one hand and the inner margin of the rim on the other hand is formed a curvilinear triangular space, there being six of such triangular spaces in the wheel. The portions of said larger segment radially inside 45 of the intersection thereof with the smaller segments are of greater width than the parts thereof adjacent to the rim, and between said larger portions of said larger segments on the 50 one hand and the hub and the smaller segment on the other hand are formed three elongated quadrilateral spaces or openings bounded by curved lines. The several segments at their ends where they are joined to the rim 55 terminate in spurs which project inwardly from the rim, as shown.

I claim as my invention—

The design for a sprocket-wheel for bicycles, substantially as herein shown and described. 60

In witness whereof I hereunto set my hand at Chicago, Illinois, this the 15th day of June, 1899.

WILLIAM H. FAUBER.
